UNITED STATES PATENT OFFICE.

HENRY SANFORD, OF NEW YORK, N. Y.

LUBRICATING DEVICE.

Application filed May 19, 1924. Serial No. 714,211.

This invention relates to the supplying of lubricating oil to automobile engines.

The objects of the invention are to make it possible for a motorist to carry a supply of 5 lubricating oil in a clean, handy transportable form and to supply the oil to the motor as required without soiling the hands or the clothing.

The foregoing and other objects are attained in this invention through certain 10 novel features of construction, combinations and relations of parts as set forth in the following specification.

In the drawings accompanying and forming 15 part of this specification, simple and practical embodiments of the invention are illustrated but it should be understood that the structural features may be modified and changed in various ways without departure 20 from the spirit and scope of the invention as hereinafter defined and broadly claimed.

Figure 1 is a broken and part sectional 25 side elevation of the combined holder and opener as applied to the oil intake of an engine and showing one of the sealed oil containers of the invention as being inserted in the holder.

Figure 2 is a broken sectional view illustrating the general relation of the holder to 30 the crank case of the motor, showing the can as completely seated in the holder and punctured to enable the oil to flow into the crank case. Figure 3 is a horizontal sectional view of the holder on substantially the plane of 35 line 3—3 of Fig. 1.

Figure 4 is a detached perspective view of 40 one of the cutters for puncturing the sealed container. Figure 5 is a broken vertical sectional view illustrating a modification in 45 which the puncturing spur is formed integral with the bottom of the casing and showing a simplified form of spring support for the can, a lighter cover construction and a shut-off valve between the casing and the oil intake. Figure 6 is a detached side elevation 50 of the one piece spring support. Figure 7 is a horizontal sectional view of the casing.

The illustration of a motor in Fig. 2 is 55 typical as showing how they are usually provided with an oil intake 5 in the side or top of the crank case, this intake being ordinarily in the form of a short standpipe equipped with a screw cap or other suitable closure.

A feature of the invention is the utilization of this oil intake as a support for a 55 special holder designed to receive a sealed container of oil and provided with means for automatically opening the sealed container by the simple act of placing the same within the holder.

In a preferred form, the sealed containers are made of substantially square or rectangular shape to facilitate handling and save space in storage. One of these substantially 65 square containers is illustrated at 6 and the holder for the same shown at 7 is of correspondingly rectangular or square outline to receive and hold the container with a fairly snug fit.

To meet a condition like that illustrated, 70 where the oil intake is equipped with a screw cap, the oil can holder is simply formed with a screw socket 8 in its lower end and is supported on the intake by simply being screwed onto the upper end of the same in place of 75 the original screw closure.

The automatic opening of the sealed can is accomplished in the illustration by mounting a cutter 9 on the bottom of the holder and by providing the holder with a hinged cover 80 10 carrying a cutter 11 for puncturing the top of the can. These cutters are shown as interchangeable, each consisting of a pointed triangular blade grooved or fluted at 12 on the rearward face of the same to provide free 85 flow for the oil or air and having a screw stem 13 by which the same may be secured with nuts 14 to the bottom or to the cover of the holder.

The cover of the tank or holder is secured closed by suitable means such as the hinged link shown at 15 adapted to snap over the keeper lug 16 on the front wall of the holder.

A spring follower is shown provided at 90 17 in the bottom of the holder for yieldingly supporting the can and holding the same against rattling. This spring follower is shown in the form of a ring engaged by a coil spring 18 supported in an enlargement 100 19 forming a spring seat in the bottom of the holder and the same in addition to the functions mentioned, operates to partially eject the emptied can when the cover is 105 opened.

The sealed oil packages, lacking screw

closed compartments or other outlets, are simple to make and can be produced quite inexpensively and a number of them can be packed together without any waste space. This makes it possible and convenient for a motorist to carry one or a number of the packages as a reserve supply, which can be fed to the motor when required, by simply slipping the cans into the holder and closing the cover down over the same. In puncturing the bottom of the can, the metal is bent back somewhat around the opening and this provides a slight cavity to collect any sediment that may be present.

The mounting of the holder on the oil intake causes the same to be supported within the region of the motor cylinders and usually fairly close to the radiator so that the oil will be warmed sufficiently to cause it to flow freely down into the crank case.

The opening of the cover enables the spring follower to lift the emptied can far enough to be easily grasped for removal and the cans can be so cheaply constructed that they may be thrown away after they have been once used. In addition to serving as a support for the cans, the holder also forms a tank and may be used as a funnel, for instance, when the crank case is to be washed out with a "flushing" oil.

In the modified construction illustrated in Figures 5 to 7 the lower cutter is shown formed as a sharp pointed triangular spur made integral with the bottom of the case and the upper cutter is shown as a sharp pointed spur 21 riveted or suitably secured to the under side of the cover 22, which in this instance is shown made of sheet metal hinged on the back of the case at 23 and secured in closed relation by an integral 40 spring catch 24.

The spring follower also is of simplified construction in that it is made of a single piece of spring metal having a raised central supporting portion 25 and bowed spring 45 arms 26 which rest on the bottom 27 of the casing at the sides of the discharge outlet.

The integrally formed can opening spur is shown as raised above the floor of the bottom on a pedestal or table projection 28 provided in one corner of the case which may act as a stop for the end of the can to prevent the can being pressed down so far as to flatten the bowed spring support and close off the discharge outlet and this pedestal also 55 may assist in positioning the spring support by preventing the same from twisting around in the bottom of the case.

If desired, a shut-off valve 29 may be interposed in the oil intake. This valve enables the flow of oil into the crank case to be governed at will and is useful, for instance, in a case where it is desired to warm the oil before permitting it to flow into the crank case. This control also enables only 60 a portion of the can being used at a time and

allows for a quantity of oil in bulk being carried in the casing and flowed into the crank case whenever it may be desired.

What is claimed is:

1. An oil can holder adapted to be connected to the oil intake of a motor, comprising a tank of non-circular cross-section having a bottom, a cutter mounted above said bottom, a hinged cover of non-circular cross-section for said tank provided with a cutter positioned between the center and the hinge side of said cover, said cutter being adapted to puncture a permanently sealed container of a cross-section corresponding to that of said tank and inserted in said holder when said cover is closed, and a spring follower in said tank for lifting said container when said cover is opened to permit grasping said container by the fingers to remove it from said tank.

2. An oil-can holding tank of non-circular cross-section provided with means for mounting the same on the oil intake of an engine crank case and having a spur projecting upwardly from the bottom of the same for piercing an oil can inserted therein, said can having a cross-section corresponding to that of said tank, said spur being mounted on a raised portion of the bottom to support the can above the bottom and a spring resting on the bottom in the space below the can.

3. In a lubricating device for a motor, an oil-can holder of non-circular cross-section having a normally open but closable connection with the oil intake of the motor, a hinged cover having a spur positioned between the center and the hinge side of said cover, for puncturing an oil can when the cover is closed, said can having a cross-section corresponding to that of said holder, and ejecting means in the bottom of the holder for ejecting the can when the cover is open.

4. In a lubricating device for a motor, an oil-can holder of non-circular cross-section having a normally open but closable connection with the oil intake of the motor, a hinged cover having a spur positioned between the center and the hinge side of said cover for puncturing an oil can when the cover is closed, said can having a cross-section corresponding to that of said holder, and a yielding member in the bottom of the holder for supporting the can and for raising the same when the cover is raised.

5. In a lubricating device for a motor, an oil can holder having a normally open but closable connection with the oil intake of the motor, a hinged cover having a spur for puncturing the oil can when the cover is closed, and a yielding member in the bottom of the holder for supporting the can and having a tension at least sufficient to raise an empty can when said cover is raised.

6. An oil can holder adapted to be connected to the oil intake of a motor, comprising a tank having a bottom, a lower cutter mounted above said bottom, a hinged cover for said tank provided with a cutter, said cutters being adapted to puncture a permanently sealed container inserted in said holder when said cover is closed, and a spring follower in said tank for lifting said container when said cover is opened to permit grasping said container by the fingers to remove it from said tank, and means for supporting said lower cutter and for providing a clearance space for said spring between the bottom of said holder and the bottom of said inserted container when said container is in its lowermost position. 15

Signed at New York, in the county of New York and State of New York, this 16th day of May, A. D. 1924.

HENRY SANFORD.
